WIRE WRAPPER BIT

Edward L. Allen, Ulster, Pa., assignor to Ingersoll-Rand Company, New York, N.Y., a corporation of New Jersey

Filed June 20, 1963, Ser. No. 289,178
5 Claims. (Cl. 242—7)

This invention relates generally to wire wrapping tools and particularly to the improvements of bit arrangements therefor and their operation.

The present invention is particularly adapted to wrapping fine gauge wire on electric terminals. It is common practice with wire wrappers which receive the free end of a wire to be wound, to provide spring biasing means for urging the wrapper bit toward a forwardmost position as shown in U.S. Patent No. 3,028,107 granted April 3, 1962 to E. T. Hjorth. During a wire wrapping operation, the bit is urged against the spring progressively as the free end of the wire is withdrawn from the bit and wrapped to form the winding. While such an arrangement is normally adequate, difficulty has been encountered in winding very small gauge wires inasmuch as one wind or lap of the wire is urged back over the preceding wind and causes bunching.

Accordingly, it is an object of this invention to provide a wire wrapping device which is particularly adapted to winding fine gauge wires.

Another object of this invention is to provide a wire wrapping device having means for urging the bit thereof backwardly toward the tool progressively during the wire wrapping operation an amount during each turn equal to the gauge of each turn of wire.

Still another object of this invention is to provide the afore-mentioned device in which the rate of retraction of the bit is derived by first use thereof.

This invention contemplates a sleeve member immovably connected to a wire wrapping tool, a bit member rotatable in the sleeve to wrap wire and having a head portion engaged by a biased keeper of the tool spindle for rotation with the spindle and for urging the head portion forwardly into engagement with the sleeve member, a plug fixed to one of the members extending outwardly therefrom toward the other member, and the other member threadedly engaging the plug to move the bit member rearwardly when rotated, the other member having an axial slot through the threads for the plug to permit the keeper to move the bit axially forwardly in the sleeve until the head contacts the sleeve when the spindle is homed.

The foregoing and other objects and advantages will appear more fully hereinafter from a consideration of the detailed description which follows, taken together with the accompanying drawings wherein several embodiments of the invention are illustrated by way of example. It is to be expressly understood, however, that the drawings are for illustration purposes only and are not to be construed as defining the limits of the invention.

FIGURE 1 is a sectional view of the front end of a wire wrapping device made in accordance with the present invention.

FIGURE 2 is an enlarged sectional view taken on line 2—2 of FIGURE 1.

FIGURE 3 is an enlarged sectional view taken on line 3—3 of FIGURE 2 illustrating the rear portion of the

2

novel bit positioned in its forwardmost position relative to the sleeve that surrounds it,

FIGURES 4 and 5 are sectional views similar to FIGURE 3 illustrating the novel bit and the sleeve that surrounds it in various other relative positions, and

FIGURE 6 is a sectional view similar to FIGURE 3 illustrating a modified embodiment of the invention.

Referring now to the drawings and particularly to FIGURE 1, only the forward end of the casing 10 is shown of a wire wrapping device or tool having a spindle 12 rotatable therein. The wire wrapping tool preferably has a homing arrangement (not shown), as an example as shown, described, and claimed in U.S. application 155,243 that was filed by J. A. Moore on November 22, 1961, now Patent No. 3,172,516, and assigned to the same assignee as the present application. Homing, as above, is to be understood as automatically returning the spindle to the same angular relationship in a tool after each wire wrapping operation. The forward end of spindle 12 is hollow and slidably houses a recessed keeper member 14 that is biased forwardly by a spring 16. A tubular clamp member 18 extends from the front end of casing 10 and is locked in position by a nut 20. A cam nut 22 is threadedly disposed on the forward end of the tubular clamp member 18, as will be further described.

A wire wrapper bit 30 is rotatably disposed in a tube or sleeve 50 and has a head portion 32 abutting the rear end of the sleeve. Sleeve 50, with the bit 30, is inserted into the tubular clamp member 18 until the bit head 32 is engaged by the recessed keeper member 14. Cam nut 22 is then threaded onto the member 18 urging its ends into clamping engagement with the sleeve 50. It will thus be seen that sleeve 50 is then held against axial movement and rotation by the clamp member 18 while the bit 30 is free to be rotated by the spindle 12 and to be moved axially against or by the force of spring 16.

Bit 30 has an axial slot 34 at its rearward end adjacent its head 32 which houses a plug or block 36, preferably of plastic or other suitable material. The forward end of bit 30 has an axial blind bore 42 to receive an electrical terminal (not shown) and a peripheral slot 40 to receive the free end of a wire (not shown) to be wrapped on the terminal in the blind bore 42. The rearward end of sleeve 50 has internal threads 52 which engage the plug 36 and cut corresponding threads 38 thereon when the bit 30 is rotated. Internal threads 52 are to correspond in size to the fine wire to be wrapped, thus, with each wind of wire caused by a single rotation of the bit 30, the threads 52 and cut threads 38 cause the bit 30 to move axially rearward a distance equal to the gauge of the wrapped wire.

Sleeve 50 has an axial slot 54 that extends through the internal threads 52 as shown in the drawings. Thus, when the wrapping operation is completed and the wire wrapping tool is stopped, the homing device (not shown) will align the plug 36 of bit 30 with the axial slot 54 of sleeve 50. Spring 16 will then urge the recessed keeper member 14 and the bit 30 axially forwardly to their starting or initial positions as shown in FIGURES 1 and 3. In practice, it has been found that the winds of wire, on a terminal being wrapped, tend to offset the forward bias of spring 16. Thus, the speed of rotation of bit 30, when slot 54 is merely sufficiently wide to accommodate plug 36, will cause threads 38 to move out of and into en-

gagement with threads 52, as the plug crosses the slot, before spring 16 can move keeper 14 and bit 30 axially. Although spring biasing means to urge a wire wrapper bit forwardly is not new as shown in the afore-mentioned Hjorth patent and in my co-pending application Serial No. 225,501 filed September 24, 1962 and assigned to the same assignee as the present application, spring 16 has a second function which is to take up backlash in the meshing threads 38 and 52 which may be caused by continuous wear.

It should now be fully understood that the present invention provides a wire wrapping bit and sleeve arrangement which provides means for driving the bit rearwardly with each turn, a distance equal to a single turn of a fine wire being wrapped, that has automatic return means when the tool is stopped and homed for returning the bit to its starting position. While the preferred embodiment of the invention is as shown, the plug 36 could be housed in the rearward end of sleeve 30 with the threads 52 and the axial slot 54 then being disposed at the rearward end of bit 30 adjacent the head 32.

Toward this end, as shown in FIGURE 6, a modified bit 30a and sleeve 50a are provided corresponding to bit 30 and sleeve 50. In this instance, sleeve 50a has a slot 34a, corresponding to slot 34, in its rearward end for retaining a plug 36a, corresponding to plug 36, against movement. Bit 30a has threads 52a, corresponding to threads 52, adjacent its head 32a corresponding to head 32. Bit 30a also has an axial slot 54a, corresponding to slot 54, which extends through threads 52a.

Although several embodiments but a single embodiment of the invention have been illustrated and described in detail, it is expressly understood that the invention is not limited thereto. Various changes may be made in the design and arrangement of the parts without departing from the spirit and scope of the invention as the same will now be understood by those skilled in the art.

I claim:

1. In combination with a wire wrapping tool having a rotatable spindle with a forwardly biased keeper:

- (a) a sleeve member connected at its rearward end to the tool and held immovable thereby;
- (b) a bit member rotatably disposed in said sleeve member and having a head portion at its rearward end engaged by said keeper to rotate the bit member when the spindle rotates and to urge the head portion axially forwardly into engagement with the rearward end of the sleeve member;
- (c) a plug fixedly connected to one of said members extending outwardly therefrom toward the other of said members;
- (d) the other of said members having threads at its rearward end engaging the plug to form threads thereon and providing a threaded connection between the two members for moving the bit member rearwardly when said bit member is rotated to wind a wire; and
- (e) the other of said members having an axial slot through the threads thereof to permit axial movement of the plug alined therewith when the spindle is stopped from rotating and the keeper urges the bit member forwardly until the head portion engages the sleeve member.

2. In combination with a wire wrapping tool having a rotatable spindle with a forwardly biased keeper:

- (a) a sleeve member connected at its rearward end to the tool and held immovable thereby;
- (b) a bit member rotatably disposed in said sleeve member and having a head portion at its rearward end engaged by said keeper to rotate the bit member when the spindle rotates and to urge the head portion axially forwardly into engagement with the rearward end of the sleeve member;
- (c) a plug fixedly connected to one of said members

extending outwardly therefrom toward the other of said members;

- (d) the other of said members having threads engaging the plug and forming meshing threads thereon cooperating to move the bit member rearwardly when said bit member is rotated to wind wire; and
- (e) the other of said members having an axial slot through the threads thereof to permit axial movement of the plug alined therewith when the spindle is stopped from rotating and the keeper urges the bit member forwardly until the head portion engages the sleeve member.

3. In combination with a wire wrapping tool having a rotatable spindle with a forwardly biased keeper:

- (a) a sleeve member immovably connected to the tool and having an axial slot in the rearward end of its inner wall;
- (b) a bit member rotatably disposed in said sleeve member and having a head portion at its rearward end engaged by said keeper to rotate the bit member when the spindle rotates and to urge the head portion axially forwardly into engagement with the rearward end of the sleeve member;
- (c) the bit member having an axial slot extending forwardly from the head portion;
- (d) a plug fixedly held in the axial slot of one of the members and extending therefrom toward the other of the members;
- (e) the other of said members having threads, interrupted by the axial slot thereof, engaging the plug and forming meshing threads thereon cooperating to move the bit member rearwardly when said bit member is rotated to wind wire; and
- (f) the plug being movable axially through the slot interrupting the threads of the other member when alined therewith and when the spindle is stopped from rotating and the keeper urges the bit member forwardly until the head portion engages the sleeve member.

4. In combination with a wire wrapping tool having a rotatable spindle with a forwardly biased keeper:

- (a) a sleeve immovably connected to the tool and having internally disposed threads at its rearward end and an axial slot through the threads;
- (b) a bit rotatably disposed in said sleeve and having a head portion at its rearward end engaged by said keeper to rotate the bit when the spindle rotates and to urge the head portion axially forwardly into engagement with the rearward end of the sleeve;
- (c) the bit having an axial slot extending forwardly from the head portion;
- (d) a plug fixedly held in the axial slot of the bit extending outwardly therefrom toward the sleeve;
- (e) the threads of the sleeve engaging the plug and forming meshing threads thereon cooperating to move the bit rearwardly when said bit member is rotated to wind wire; and
- (f) the plug being movable axially in the slot in the sleeve through the threads when alined therewith and when the spindle is stopped from rotating to permit the keeper to urge the bit forwardly in the sleeve until the head portion engages the rearward end of the sleeve.

5. In combination with a wire wrapping tool having a rotatable spindle with a forwardly biased keeper:

- (a) a sleeve immovably connected to the tool and having an internally disposed axial slot at its rearward end;
- (b) a bit rotatably disposed in said sleeve and having a head portion at its rearward end engaged by said keeper to rotate the bit when the spindle rotates and to urge the head portion axially forwardly into engagement with the rearward end of the sleeve;
- (c) the bit having threads extending forwardly from

- the head portion and an axial slot through the threads;
- (d) a plug fixedly held in the axial slot of the sleeve extending outwardly therefrom toward the bit;
- (e) the threads of the bit engaging the plug and forming meshing threads thereon cooperating to move the bit rearwardly when said bit is rotated to wind wire; and
- (f) the plug being movable axially in the slot in the bit through the threads when alined therewith to permit the keeper to urge the bit forwardly in the sleeve until the head portion engages the rearward end of the sleeve when said bit is stopped from rotating.
